Des. 221,894
Patented Sept. 14, 1971

221,894

COMBINED ELECTRIC LANTERN AND MOVEABLE HANDLE THEREFOR

Nolan K. Rhoades, Beloit, Wis., assignor to
ESB Incorporated

Filed Feb. 27, 1970, Ser. No. 21,660

Term of patent 14 years

Int. Cl. D26—02

U.S. Cl. D48—24

Fig. 1

Fig. 3

Fig. 2

Fig. 6

Fig. 5

Fig. 4

FIG. 1 is a front perspective view of a combined electric lantern and moveable handle therefor showing my new design, with the handle in a supporting position; FIG. 2 is a front elevational view thereof; FIG. 3 is a side elevational view thereof; FIG. 4 is an opposite side elevational view thereof; FIG. 5 is a rear elevational view thereof; and FIG. 6 is a top plan view thereof.
I claim:

The ornamental design for a combined electric lantern and moveable handle therefor, as shown and described.
